UNITED STATES PATENT OFFICE.

WILLIAM J. HOSCEIT, OF TOPEKA, KANSAS, ASSIGNOR TO NATIONAL DUMP CAR COMPANY, OF CHICAGO, ILLINOIS, A CORPORATION OF MAINE.

DUMP-DOOR-OPERATING MECHANISM.

1,112,617.

Specification of Letters Patent.

Patented Oct. 6, 1914.

Application filed September 26, 1910. Serial No. 583,788.

To all whom it may concern:

Be it known that I, WILLIAM J. HOSCEIT, a citizen of the United States, residing at Topeka, in the county of Shawnee and State of Kansas, have invented certain new and useful Improvements in Dump-Door-Operating Mechanism, of which the following is a specification.

My invention relates to dump cars and has particular reference to improved means for operating the dump doors.

My improvements have been directed chiefly to the hopper type of cars which have sloping end walls leading to a central discharge opening, though they may be applied to other forms of dump cars.

The object of my improvements is to provide mechanism for operating movable supporting shafts, which in their supporting positions are adjacent the meeting edges of hinged dump doors. My improvements may be used in other connections and are not limited to the arrangement of doors above mentioned.

A particular object of my invention is to provide means for simultaneously moving the door supporting shafts either toward or away from their door supporting positions at the will of the operator, said means being located at each side of the car and adapted to be actuated by the operator at either side. The means employed for accomplishing the above object comprise members having vibratory or oscillatory movements and an important object has been to render the said members capable of transmitting the power of the operator to the door supporting mechanism while its vibratory movements in both directions are being effected.

Other objects of my improvements will become more apparent in the following specification and claims, taken in connection with the accompanying drawings in which—

Figure 1 is a side elevation of a car of the hopper type with my improvements applied thereto. Fig. 2 is a section of the lower portion of said car taken substantially on the line 2, 2 of Figs. 1 and 3. Fig. 3 is a longitudinal section of the lower portion of the car taken substantially on the line 3, 3 of Fig. 2, some of the parts being shown in elevation. Fig. 4 is a horizontal section of a portion of the lower part of the car taken

substantially on the line 4, 4 of Fig. 3. The line 4, 4 of Fig. 3 is irregularly placed to permit parts to be shown in this view which lie above the general plane of the section. Fig. 5 is a sectional view in detail showing the ratchet bar carrying links and the arms 60 on which they are suspended. Fig. 6 is a perspective view of a detail showing the manner in which the operating lever is connected with the movable ratchet bar guides. Fig. 7 is a detail showing a portion of one 65 of the ratchet bars in its relation to the ratchet wheels when disengaged therefrom. Fig. 8 is a detail showing one of the ratchet bar elevating levers.

In the drawings I have preferred to illustrate my improvements in connection with a car of the hopper type constructed chiefly of steel. In said car the side walls 10 are made of steel plates and the sloping end plates 11 are secured to said side walls. The 75 sloping floor plates 12 are secured to said side walls and are also suitably secured to the sloping end walls. The sloping floor plates 12 terminate in vertical portions 13 at their lower edges and serve as side walls 80 for the central discharge opening. The sloping end walls 11 also terminate in vertical portions 14, which, in a similar manner, serve as end walls for the said discharge opening. The central discharge 85 opening is divided into two parts by vertical plates 15 and 16, which are placed transversely of said discharge opening and are suitably secured to the side walls 13. These vertical plates 15 and 16 are provided 90 with sloping upper portions 17 and 18 which converge and meet in flanges 19 which are secured together. The vertical walls 14, 15, 16, &c., terminate in horizontally disposed flanges 20, 21, 22, &c., against which the 95 bodies 23 of the doors bear in their closed positions. The framework of the car also includes longitudinally disposed members 25, which are preferably channel bars and against which the vertical portions of the 100 plates 12 are secured. The framework also includes longitudinally disposed angle bars 26 which are secured to the lower edges of the side walls 10. Between the channel bars 25 and the angle bars 26 are placed the 105 struts or stays 27, which are suitably secured to said members 25 and 26. The transversely disposed plates 28 are attached

to the vertical plates 15 and 16 and these plates 28, taken in connection with said plates 15 and 16, serve to form a housing or covering for the greater part of the door operating mechanism. The upper edges of these plates 28 are flanged as shown at 29 and 30 and the said flanged portions are placed against the lower flanges of the channel bars 25 and may be secured thereto. 5 These plates 28 preferably extend the whole width of the car and terminate beneath the outer edge of the angle bars 26.

10 The plates 23 of the dump doors are provided with ribs 31 upon their lower surfaces, which serve as stiffening ribs for said doors and also as convenient means upon which the rollers 33 may operate. The ribs 31 are spaced from the doors at their inner edges by flanged members 31^a. A flanged member 31^a 15 is also placed between the door 23 and the rib 31 and has a position lying parallel to the said ribs. The ribs 31 have a portion 31^b at their inner ends which is substantially parallel to the tracks 34 when the doors are closed, 20 as will be more fully described later. The ribs 31 also have a portion 31^c having a greater slope than the portion 31^b and extending from the latter to a point near the middle of the body 23 of the door. The rib 31 is given an upward turn at its outer end 31^d to which are attached the hinges 31^e. 25 These hinges are suitably attached to the frame members 25.

30 The rollers 33 are mounted upon the shafts 32, which shafts are in turn supported by the track bars 34. The inner edges of the dump doors 23 are supported in their closed positions by the said shafts 32. These shafts are preferably square in form and carry 35 gears 36, which have hubs 35 of considerable length and cylindrical in form. These hubs serve as convenient bearings for the rollers 33 and also serve as rollers for supporting the shafts as they move upon the tracks 34.

40 The track bars 34 have a position preferably inclined slightly from the horizontal and are provided with upwardly turned inner ends 34^a which are riveted or otherwise suitably secured to the plates 28. The outer 45 ends of the bars 34 are upwardly turned and secured to the struts 27 by the rivets 34^b. The track bars are provided with pins or teeth 37 which mesh with the teeth of the gears 36, and when the gears 36 are rotated 50 the shafts will be caused to travel along said tracks. The track bars 39, adjacent the outer ends of the shaft 32, are in every respect similar to the track bars 34 in their essential features. The gears 38, fixed to the 55 outer ends of the shafts 32, are also similar to the gears 36.

60 My improvements are largely directed to the means for rotating the shafts 32 and this mechanism will now be described.

65 At the middle of the length of one of the

shafts 32 are mounted ratchet wheels 40 and 41. These ratchet wheels have square apertures which fit the square shafts 32, and hence are non-rotatably fixed to said shafts. The other of the shafts 32 is also provided with similar ratchet wheels 42 and 43, also non-rotatably fixed to said shafts. The teeth of the ratchet wheel 40 slope in opposite directions to the teeth of the ratchet wheel 41. The teeth of the ratchet wheel 42 slope in opposite directions to those of the ratchet wheel 41. It will therefore be seen that each of the shafts 32 is provided with a pair of ratchet wheels having teeth which slope in opposite directions. Immediately 70 above the said ratchet wheels are ratchet bars 44 and 45 arranged transversely of the car and adapted to engage the said ratchet wheels in pairs. In other words, one of the ratchet bars 44 is adapted to engage one of the ratchet wheels on each shaft, and the other ratchet bar 45 is adapted to engage another ratchet wheel on each shaft. The teeth of the ratchet bars 44 and 45 also slope 75 in opposite directions. This is necessary to enable them to properly mesh with the ratchet wheels directly beneath them. Each of the said ratchet bars comprises two inclined portions which meet at the center of the car and have an inclination substantially 80 parallel to the track bars 34. One of the ratchet bars 44 is adapted to engage the ratchet wheel 40 on one of the shafts 32 and the ratchet wheel 43 on the other of said shafts 32. The teeth of the ratchet wheels 85 40 and 43 slope in opposite directions, and hence the teeth of the inclined portions of the bar 44 must also slope in opposite directions to properly mesh with said wheels. The ratchet bar 45 is adapted to engage the 90 ratchet wheel 41 on one of the shafts 32 and the ratchet wheel 42 on the other of the shafts 32. These ratchet wheels 41 and 42 also have teeth which slope in opposite directions. The teeth of the ratchet bar 45 also 95 slope in opposite directions.

100 The ratchet bar 45 and the two wheels 41 and 42 which engage it are in every respect similar to the ratchet bar 44 and its associated ratchet wheels 40 and 43, except that the teeth in each case slope in opposite directions. In other words, there are two groups, each of which groups comprises a ratchet bar and two ratchet wheels. The corresponding teeth in the two groups 105 slope in opposite directions. The group comprising the ratchet bar 44 and the two ratchet wheels 40 and 43 has teeth of such slope that when the ratchet bar 44 is reciprocated, the ratchet wheels will be given such a direction of rotation as will cause 110 them to move toward the center of the car. This group is shown in Fig. 2. The group comprising the ratchet bar 45 and the ratchet wheels 41 and 42 has teeth of such a slope 115

as will cause them to move away from the center of the car when the ratchet bar 45 is reciprocated.

From the above description it will be seen that if one of the ratchet bars is placed in engagement with its ratchet wheels and is reciprocated, the shafts 32 may be moved toward the center of the car. When this is done the other ratchet bar must be disengaged from its ratchet wheels. When it is desired to cause the shafts 32 to move away from the center of the car the connections between the ratchet bars and the ratchet wheels must be reversed.

15 The ratchet bars 44 and 45 lie upon each side of the central movable plate 46 and are preferably in contact therewith. Adjacent the extreme ends of the ratchet bars are clips 47 and 48 which overlap said ends and

20 which are riveted to the said movable plate 46. These clips 47 and 48 serve as vertical guides for the ratchet bars. The ratchet bars have a slight vertical movement equal to or slightly in excess of the depth of the

25 teeth. This vertical movement is necessary to permit the engagement and the disengagement with the ratchet wheels. This vertical movement is also necessary to permit a slight tilting of the ratchet bar when

30 it slips over the teeth of one of the ratchet wheels during a stroke in one direction and while it is imparting motion to the other of its ratchet wheels.

The movable plate 46 is provided with angle bars 49 and 50 attached to its upper edge and extending the full length of said plate. The horizontally disposed flanges of said angle bars rest upon brackets 51 and 52 and are guided thereby. These brackets

40 are secured to the framework of the car through means of the intermediate hangers 52^a and 51^a. These hangers are secured to the angle bars 26 of the framework.

The movable plate 46 is given a reciprocating movement by the lever 53, which has an upwardly extending arm 54 which is fitted into a notch or socket 54^a in said plate and in the angle bars fixed thereto. The lever 53 is pivoted upon the pin 55, which

50 is carried by the sleeves 58 which are fixed to the plates 28. The lever 53 has a downwardly extending portion below the pivot 55, which is provided with a socket 56 adapted to receive an operating lever 57.

55 This operating lever is preferably given a tapered end which may be conveniently inserted in the socket 56 by the operator when the latter desires to actuate the dump door operating mechanism.

60 In order to raise the ratchet bars out of engagement with their ratchet wheels, the links 59, 60, 61 and 62 are provided. These links are pivotally attached to the ratchet bars at 63, 64, 65, &c. The upper ends of

65 these links are provided with slots 67, which

engage arms 68, 69, 70 and 71 which are oppositely disposed in pairs on the shaft 72. The shaft 72 is provided with suitable bearings in the framework of the car. The shafts may pass through the side walls 13, 70 channel bars 25 and may be supported at their outer ends in bearings 73, 74. These bearings are supported by the hangers 51^a and 52^a. At the extreme outer ends of the shafts are small hand levers or cranks 75 and 76. By means of these hand levers the shaft 72 may be rotated in one direction or the other through a small angle. This movement will cause either one of the ratchet bars 44 or 45 to be elevated while the other is being lowered. This is effected by means of the links 59 and 60, 61 and 62 which are suspended from said arms 68, 69, 70 and 71.

In order to permit the previously described tilting of the ratchet bars while they are slipping over their ratchet wheels, the slots 67 in links 59, 60, 61 and 62 are provided. These slots have sufficient length to permit an upward movement which results from the said tilting movement. The links are guided by the angle bars 49 and 50, in which are apertures 49^a and 50^a in which the said links have a sliding movement.

The operation and use of my invention is substantially as follows: The operator first places the particular ratchet bar into engagement with its ratchet wheels which will cause a movement of the shafts 32 in the direction desired. If, for example, he desires to dump the load, he will rotate either of the levers 75 or 76 in such a direction as to cause the ratchet bar 45 to become engaged with the ratchet wheels 41 and 43. The same movement will cause the ratchet bar 44 to become disengaged from the ratchet wheels 40 and 42. Upon examining Fig. 7, it will be seen that the teeth of the ratchet bar 45 have such a slope as will cause an outward rotation of the ratchet wheels 41 and 43 when the said ratchet bar 45 is reciprocated. In the movement of the ratchet bar in one direction, the teeth will engage the ratchet teeth 41 and will slip over the teeth in the ratchet wheel 43. In the reverse movement of the said ratchet bar the teeth will engage the wheel 43 and slip over the teeth in wheel 41. There will be an alternating step by step movement given to the ratchet wheels. The rotary movement thus produced in the ratchet wheels 43 will cause them to give a like rotary motion to the gear 36. The teeth of the gear 36 will engage the teeth 37 of the tracks 34 and an outward movement of the shafts will result. The shafts will roll along the tracks 34 until they reach the first bends in the ribs 31. As soon as they have passed these bends the roller 33 will more easily roll upon the inclined portions 31^c and the load in the car will greatly assist in causing a

130

further opening movement of the doors. The operator inserts the hand lever 57 in one of the sockets 56 on the side of the car near which he may be standing, and upon giving a vertical oscillating movement to the said hand lever the arm 53 will impart a reciprocating movement to the plate 46. The plate 46 will in turn impart its movement to the ratchet bars 44 and 45 by means of the clips 47 and 48. These clips bear upon the extreme end of the ratchet bars when imparting the said reciprocating movement thereto. When the operator desires to restore the doors to their closed positions he disengages the ratchet bar 45 from the ratchet wheels 41 and 43 and causes the ratchet bar 44 to become engaged with the ratchet wheels 40 and 42. This he does by rotating either of the hand levers 75 or 76 in such direction as will raise the bar 45 and allow the bar 44 to drop into engagement with its ratchet wheels. He then gives to the lever 57 a vertical oscillating movement and the shafts 32 are given a rotary movement in the opposite direction to that previously described.

It will be seen that the dump door operating mechanism may be operated from either side of the car. It will also be seen that no further adjustments are necessary after moving either of the levers 75 or 76 to the right or the left when it is desired to dump the load. When it is desired to restore the doors to their closed position, it is necessary only to move either of the levers 75 or 76 to their original position.

It will be seen that the track bars 34 which support the shafts 32 are rigidly secured to the transverse framework which lies across the bottom of the car. It will further be seen that this framework is of a very substantial construction. It will also be seen that the downward and inward slope of the track bars 34 counteracts any tendency of the said supporting shafts 32 to become accidentally dislodged from their normal positions. It will also be seen that the shafts 32 are substantially locked in their normal positions by one of the ratchet bars. The teeth of the ratchet bar 44 are normally in engagement with the ratchet wheels 40 and 42 and the weight of said ratchet bar causes this engagement to be maintained. The weight of the levers 75 and 76 will be effective in holding the shaft 72 in the position occupied while the doors are being closed and there will be no tendency to raise the ratchet bar 44. The levers 75 and 76 will naturally be left in this position by the operator when he has completed the closing movement of the doors.

While I have described more or less precisely the details of construction, I do not wish to be understood as limiting myself thereto, as I contemplate changes in form

and the proportion of parts and the substitution of equivalents as circumstances may suggest or render expedient without departing from the spirit of my invention.

I claim:

1. In a car having a dump door, a shaft for holding said door in a closed position, and a ratchet bar adapted to move said shaft with relation to its holding position. 70

2. In a car having a dump door, a shaft for holding said door in a closed position, a ratchet wheel fixed to said shaft, and a ratchet bar adapted to engage said wheel and to give said shaft a movement with relation to its supporting position. 75

3. In a car having a dump door, a shaft for holding said door in a closed position, a ratchet wheel fixed to said shaft, a ratchet bar adapted to engage said wheel and to give it a rotary motion when reciprocated, and means by which said rotary motion may cause a movement of said shaft with relation to its supporting position. 80

4. A car having a bottom comprising a dump door, a supporting shaft for said door, a ratchet wheel fixed on said shaft, a ratchet bar meshing with and adapted to rotate said ratchet wheel in one direction when given a reciprocating movement, and means whereby the rotation of said shaft causes its displacement from its supporting position. 85

5. A car having a bottom comprising a dump door, a supporting shaft for said door, a ratchet wheel fixed on said shaft, a ratchet bar meshing with and adapted to rotate said ratchet wheel in one direction when given a reciprocating movement, means whereby the rotation of said shaft causes its displacement from its supporting position, and means by which said bar may be actuated from either side of the car. 90

6. A car having a bottom formed of doors, said doors being arranged in separate series oppositely disposed with relation to the central line of the car body, a supporting shaft for each series, a ratchet wheel fixed on each shaft, a ratchet bar meshing with each ratchet wheel and adapted to rotate said wheel in one direction when given a reciprocating movement, means by which the rotation of said supporting shafts causes their displacement from their supporting positions, and means by which said bar may be actuated from either side of the car. 100

7. A car having a bottom formed of dump doors, shafts for supporting said doors, a ratchet wheel fixed on each shaft, a ratchet bar meshing with each ratchet wheel and adapted to rotate said wheel in one direction when given a reciprocating movement, and means by which said bar may be actuated from either side of the car. 110

8. A car having a bottom formed of dump doors, shafts for supporting said doors, a ratchet wheel fixed on each shaft, the teeth 115

- on said wheels being disposed in opposite directions, a ratchet bar having separate series of teeth, the teeth in one series having an opposite slope to those in the other series 5 in order to mesh with said wheel teeth, said ratchet bar being adapted to be moved into engagement with said wheels and to rotate said wheels when given a reciprocating movement.
- 10 9. A car having a bottom comprising dump doors, supporting shafts for said doors, a ratchet wheel on each of said shafts, a bar having ratchet teeth and adapted to reciprocate adjacent said wheels, said bar being adapted to engage the teeth of the wheel on one of said shafts and to cause rotation thereof when given a movement in one direction and to engage the teeth of the wheel on the other shaft and to cause rotation thereof when given a movement in the other direction.
- 15 10. A car having a bottom comprising dump doors, supporting shafts for said doors, a ratchet wheel on each of said shafts, a bar having ratchet teeth and adapted to reciprocate adjacent said wheels, said bar being adapted to engage the teeth of the wheel on one of said shafts to cause a rotation thereof and to slide over the teeth of the other wheel 20 when given a movement in one direction, said bar also being adapted to engage said second named wheel to cause a rotation thereof and to slide over the teeth of the first named wheel when given a movement in the opposite direction.
- 25 11. A car having a bottom comprising dump doors, supporting shafts for said doors, a ratchet wheel on each of said shafts, a bar having ratchet teeth and adapted to reciprocate adjacent said wheels, said bar being adapted to engage the teeth of the wheel on one of said shafts and to cause a rotation thereof and to slide over the teeth of the other wheel when given a movement in one direction, said bar also being adapted to engage said second named wheel to cause a rotation thereof and to slide over the teeth of the first named wheel when given a movement in the opposite direction, and means 30 whereby the rotation of said shafts causes a movement with relation to their supporting positions.
- 35 12. A car having a bottom comprising a pair of dump doors, a supporting shaft for each door, a pair of ratchet wheels fixed on each shaft and having oppositely sloping teeth, a pair of ratchet bars adjacent said wheels, each of said bars being adapted to mesh with and operate two of the wheels, one of which is fixed on each shaft, and to cause a movement thereof with relation to its supporting position, and means for imparting a reciprocating movement to said bars.
- 40 13. A car having a bottom comprising a pair of dump doors, a supporting shaft for each door, a pair of ratchet wheels fixed on each shaft and having oppositely sloping teeth, a pair of ratchet bars adjacent said wheels, each of said bars being adapted to mesh with and operate two of the wheels, one of which is fixed on each shaft, and to cause a movement of said shafts with relation to their supporting positions, means under control of the operator for causing the engagement of either of said ratchet bars with its respective ratchet wheels, and means for imparting a reciprocating movement to said bars.
- 45 14. A car having a bottom comprising a pair of dump doors, a supporting shaft for each door, a pair of ratchet wheels fixed on each shaft and having oppositely sloping teeth, a pair of ratchet bars adjacent said wheels, each of said bars being adapted to mesh with and operate two of the wheels, one of which is fixed on each shaft, and to cause a movement of said shafts with relation to their supporting positions, means under control of the operator for causing the engagement of either of said ratchet bars with its respective ratchet wheels and the disengagement of the other of said bars from its respective ratchet wheels, and means for imparting a reciprocating movement to said bars.
- 50 15. A car having a bottom comprising a pair of dump doors, a supporting shaft for each door, a pair of ratchet wheels fixed on each shaft and having oppositely sloping teeth, a pair of ratchet bars adjacent said wheels, each of said bars being adapted to mesh with and operate two of the wheels, one of which is fixed on each shaft, and to cause a movement of said shafts with relation to their supporting positions, means under the control of the operator on either side of the car for causing the engagement of either of said ratchet bars with its respective ratchet wheels, and means for imparting a reciprocating movement to said bars.
- 55 16. A car having a bottom comprising a pair of dump doors, a supporting shaft for each door, a pair of ratchet wheels fixed on each shaft and having oppositely sloping teeth, a pair of ratchet bars adjacent said wheels, each of said bars being adapted to mesh with and operate two of the wheels, one of which is fixed on each shaft, and to cause a movement of said shafts with relation to their supporting positions, means under the control of the operator on either side of the car for causing the engagement of either of said ratchet bars with its respective ratchet wheels and the simultaneous disengagement of the other of said ratchet bars from its respective ratchet wheels, and means for imparting a reciprocating movement to said bars.
- 60 17. A car having a bottom comprising a pair of dump doors, a supporting shaft for each door, a pair of ratchet wheels fixed on each shaft and having oppositely sloping teeth, a pair of ratchet bars adjacent said wheels, each of said bars being adapted to mesh with and operate two of the wheels, one of which is fixed on each shaft, and to cause a movement of said shafts with relation to their supporting positions, means under the control of the operator on either side of the car for causing the engagement of either of said ratchet bars with its respective ratchet wheels and the simultaneous disengagement of the other of said ratchet bars from its respective ratchet wheels, and means for imparting a reciprocating movement to said bars.
- 65 18. A car having a bottom comprising a pair of dump doors, a supporting shaft for each door, a pair of ratchet wheels fixed on each shaft and having oppositely sloping teeth, a pair of ratchet bars adjacent said wheels, each of said bars being adapted to mesh with and operate two of the wheels, one of which is fixed on each shaft, and to cause a movement of said shafts with relation to their supporting positions, means under the control of the operator on either side of the car for causing the engagement of either of said ratchet bars with its respective ratchet wheels and the simultaneous disengagement of the other of said ratchet bars from its respective ratchet wheels, and means for imparting a reciprocating movement to said bars.

17. A car having a bottom comprising a pair of dump doors, a supporting shaft for each door, a pair of ratchet wheels fixed on each shaft and having oppositely sloping teeth, a pair of ratchet bars adjacent said wheels, each of said bars being adapted to mesh with and operate two of the wheels, one of which is fixed on each shaft, and to cause a movement of said shafts with relation to their supporting positions, and means for imparting a reciprocating movement to said bars, said means being adapted to be operated from either side of the car.

18. A car having a bottom comprising a pair of dump doors, a supporting shaft for each door, ratchet wheels on each shaft for imparting movements in either of two directions to said shafts with relation to their supporting positions, a ratchet bar adapted to engage the ratchet wheels which produce a movement in one direction relative to said supporting positions and another ratchet bar adapted to engage the ratchet wheels which produce movement in another direction relative to said supporting positions, means for causing either of said ratchet bars to become engaged with its respective wheels, and means for actuating said ratchet bars.

19. In a car having a bottom comprising a plurality of dump doors, a supporting shaft for each door, a ratchet bar adapted to move said shafts with relation to their supporting positions, a carrying means for said ratchet bar, and means for actuating said bar.

20. In a car having a bottom comprising a plurality of dump doors, a supporting shaft for each door, a ratchet bar adapted to move said shafts with relation to their supporting positions, a carrying means for said ratchet bar, and means for actuating said bar, said actuating means being adapted to be operated from either side of the car.

21. In a car having a bottom comprising a plurality of dump doors, a supporting shaft for each door, a ratchet bar adapted to move said shafts with relation to their supporting positions, a carrying means for said ratchet bar, means for guiding said bar in its movement into and out of engagement with said shafts, and means for actuating said bar.

22. In a car having a bottom comprising a plurality of dump doors, a supporting shaft for each door, a ratchet bar adapted to move said shafts with relation to their supporting positions, a carrying means for said ratchet bar, a reciprocating member carried by the frame for actuating said ratchet bar, said reciprocating member being adapted to permit a movement of said bar into and out of engagement with said shafts, and means for actuating said reciprocating member.

23. In a car having a bottom comprising a plurality of dump doors, a supporting shaft for each door, a ratchet bar adapted

to move said shafts with relation to their supporting positions, a carrying means for said ratchet bar, said carrying means being adapted to move said ratchet bar into and out of engagement with said shafts at the will of the operator, and means for actuating said bar.

24. In a car having a bottom comprising dump doors, supporting shafts for said doors, a plurality of ratchet wheels on said shafts, a plurality of ratchet bars adapted to engage said wheels and move them with relation to their supporting positions, said bars being adapted to give opposite movements to said shafts, means for moving either of said bars into engagement with their respective shafts, a reciprocating member carried by the car body adapted to impart reciprocating movements to said bars, and means for actuating said reciprocating member at the will of the operator.

25. In a car having a dump door, a shaft for holding said door in a closed position, a ratchet bar adapted to move said shaft with relation to its holding position, and means by which the operator may actuate said ratchet bar.

26. In a car having dump doors, means for supporting said doors in their closed positions, means for displacing said supporting means from their supporting positions, and oscillating means at both sides of said car for actuating said displacing means.

27. In a car having dump doors, means for supporting said doors in their closed positions, means for displacing said supporting means from their supporting positions, oscillating means at both sides of said car for actuating said displacing means, and means operable from either side of said car for causing said displacing means to impart movements in opposite directions to said supporting means.

28. In a car having dump doors, means for moving said doors to and from their closed positions, reciprocating members for operating said means, and oscillating means at both sides of said car for actuating said reciprocating members.

29. In a car having dump doors, means for moving said doors to and from their closed positions, reciprocating members for operating said means, means at both sides of said car for actuating said reciprocating members, and means operable from either side of said car for reversing the direction of movement imparted to said moving means by said reciprocating members.

30. In a car having a bottom comprising dump doors, shafts for supporting said doors in their closed positions and adapted to move to and from their supporting positions, reciprocating means adapted to engage said shafts and move them to and from their supporting positions, and oscillating

means at both sides of the car, either of which is adapted to actuate said reciprocating means.

31. In a car having a bottom comprising 3 dump doors, shafts for supporting said doors in their closed positions and adapted to move to and from their supporting positions, means for moving said shafts relatively to said positions, and oscillating means at both 13 sides of the car, either of which is adapted to actuate said means for moving the supporting shafts on both sides of said car.

32. In a car having a bottom comprising

dump doors at both sides thereof, means for supporting and operating said dump doors, 15 and oscillating means at both sides of said car, either of which means is adapted to actuate said means for supporting and operating said doors at both sides of said car.

In testimony whereof, I have subscribed 20 my name.

WILLIAM J. HOSCEIT.
